UNITED STATES PATENT OFFICE.

SAMUEL WEINTRAUB, OF NEW YORK, N. Y.

BOTTLE CAP.

Application filed November 13, 1923. Serial No. 674,471.

This invention relates to improvements in bottle caps or closures for liquid containing receptacles and more particularly for such as contain aerated or carbonated beverages.

5 One of the objects of the invention is to provide a crown cap capable of effectually sealing a bottle when applied and retain its contents in a state of perfect preservation until required.

10 Another purpose is to produce a bottle cap that can be removed by an easy manual operation applied at the initial stage and completed by the force of the air or gas contained within the bottle.

15 A further aim is in the provision of an essentially cheap, sanitary and simple cap, capable of being applied expeditiously by ordinary bottle capping machines with less than the usual danger to the container.

20 These and similar aims and objects, which will later appear, are accomplished by the novel construction, combination and arrangement of parts hereinafter described and shown in the accompanying drawing, forming an essential part of this disclosure, and in which:—

Figure 1 is a top plan view of an embodiment of the invention, illustrating its application.

25 Figure 2 is a transverse sectional view of the same, showing the cap in a seated or operative position.

30 Figure 3 is a similar sectional view but showing the cap in a partially raised position preliminary to complete removal.

Referring more in detail to the drawing, the numeral 5 designates the neck of a conventional type of bottle, having an annular enlargement 6 near its reduced bead 7 at 35 the mouth 8, the bead blending into the enlargement by a curved, circumferential groove 9, such forms of bottles being of common occurrence.

40 The closure includes a disc 10 of pliable, yielding material, suited to seat upon the bottle top, covering the mouth and acting as a seal, cork being preferred as the material for manifest reasons.

45 Over the upper surface of the cork is disposed a thin sheet or disc of waxed or paraffined paper 11, the treated paper and cork both being non-absorbent and not affected by the liquids with which they may come in contact.

50 A crown 12 made of aluminum, relatively

stiff and having a certain degree of resiliency, has formed on it a downturned or flanged edge 13 which rests upon the margin of the cork 10 at the edge of the disc 11.

This crown is slightly concavo-convex, 60 there being a space 14 normally below it, over the disc 11, and at the raised center of the crown is a semi-circular protuberance 15.

The cover is composed of a plate 16 having a downwardly curved edge 17 blending into a cylindrical skirt or flange 18 which extends, when applied to the bottle, over the recess 9, and is crimped to produce undulations 19 which tightly engage under the bead 7, holding the entire structure firmly in 70 place.

Experience has developed the fact that the best results are attained when this cover is made of relatively thin and very soft aluminum, the metal being non-corrosive, cleanly of pleasing appearance and amendable to being drawn into its original cup shape, as well as easily crimped to adhere to the bottle neck with little or no danger of breaking or chipping the same, occurrences which frequently happen with harder metals.

The lower surface of the cup-shaped cover 16 normally rests on the tip of the protuberance 15 and its outer surface is provided with weakening slits 20, passing only partially 85 through the metal, these slits taking the form of opposed arches terminating in the solid metal at one end and joined at the other by a similar weakening slit 21 concentric with the outline of the cover, these lines bounding 90 a tongue 22 which may be readily separated from the body of the cover by inserting a finger nail, pin or other pointed article at the point 23 on the cover which is slightly depressed for that purpose.

95 As the metal of the cover is quite thin and very soft, the tongue may be raised without difficulty, permitting the crown to rise, which in practice it is found to do automatically, loosening the disc 11 and cork, thus allowing the gas contained in the beverage to escape, forcing the cork upward into the cover to the extent of raising the entire structure free of the bottle mouth.

100 It has been found in practice that enough force is invariably exerted by the confined gas in ordinary aerated beverages to raise the cover, smoothing out the corrugations and free the cap, immediately upon rupturing the tongue 22 provided the parts be prop- 110

erly proportioned in the manner herein described and that tearing or rupture of the tongue is easily accomplished.

It is however evident that various minor changes might be resorted to without departing from the spirit and scope of the invention as claimed, hence I do not wish to limit myself to the exact construction shown.

Having thus described my invention, what I claim as new and desire to secure by Letters Patent, is:—

1. In a cap for bottles containing carbonated fluid, a sealing disc for the open top of the bottle, a crimped cup-shaped member fitted on the top of the bottle and normally holding the disc in sealing position, cooperating means between the disc and the cup shaped member adapted to be actuated to permit the gas in said bottle to unseat and 20 remove the cup-shaped member from the bottle.

2. In a cap for bottles containing aerated or carbonated fluid, a sealing disc for the open top of the bottle, a cup shaped member 25 fitted on the top of the bottle and having weakened lines in its upper surface defining a tongue, a concavo-convex spring plate interposed between the cup shaped member and said sealing disc, a central protuberance 30 formed on said plate and normally in contact with the underside of said tongue whereby

said disc is maintained in a sealing position, said disc being unseated upon the actuation of the tongue to permit the protuberance to move upwardly through the cup-shaped member and whereby to permit the gas in the bottle to unseat the disc and remove the cup-shaped member from the bottle. 35

3. In a bottle cap for bottles containing aerated or carbonated fluid, a cork disc adapted to rest on the open top of the bottle, a substantially concavo-convex spring metal crown having a marginal flange engaging the peripheral edge of said cork disc, a central protuberance formed on said crown, a plate 40 disposed above the crown, a depending crimping flange formed on said plate adapted for engagement with the beaded neck portion of the bottle, said plate having weakened lines formed therein to form a tongue, 45 said tongue normally engaging the aforementioned protuberance for maintaining the cork disc in a sealing position, the gas confined in the bottle being adapted to unseat the disc and automatically release the 50 crimped plate from the bottle when the tongue is lifted upwardly out of engagement with said protuberance.

Signed at New York, in the county of New York and State of New York, this 23rd day of October A. D. 1923.

SAMUEL WEINTRAUB.
